DANIEL SHERWOOD, OF LOWELL, MASSACHUSETTS, ASSIGNOR TO WOODS,
SHERWOOD & CO., OF SAME PLACE.

Letters Patent No. 96,977, dated November 16, 1869.

IMPROVEMENT IN HANGING BASKET.

The Schedule referred to in these Letters Patent and making part of the same

To all whom it may concern:

Be it known that I, DANIEL SHERWOOD, of Lowell, in the county of Middlesex, and State of Massachusetts, have invented a new and improved Hanging Basket, of which the following is a specification.

The object of my invention is to produce an ornamental basket or receptacle for holding flowers, plants, &c., combining strength with beauty, to hang in windows, alcoves, &c.; and

It consists in constructing such a basket, and its suspenders, of twisted wire, and with a vessel of the same form as the basket, placed therein, to hold the flowers and plants.

In the drawings—

Figure 1 is a view of the basket, complete, and Figure 2 shows the details of construction.

A is the ring forming the rim of the basket. It is composed of two strands of wire, of suitable size and length, twisted together and united at the end.

B are the ribs, formed as shown in fig. 2, the ends of which are bent, to embrace the rim A, and also the small ring a, forming the bottom of the basket.

These ribs are also formed in pairs, of one piece of

wire, with the looped end bent down to embrace the rim A, and then bent up to form the ear b, fig. 2, for the purpose of forming a means of attachment for the chains or suspenders.

The links of the chains are formed of twisted wire, bent to the proper shape, either of a square or other form.

The several parts of the basket, when completed, are coated with tin, by immersion in a bath, to prevent corrosion.

The basket is furnished with a dish or vessel, C, to hold water for preserving the flowers, &c.

I claim, as a new article of manufacture—

The hanging basket, constructed of twisted wire, provided with suspenders of the same material, and a receptacle within, and of the same conformation as the basket for holding the flowers, &c., substantially as described and set forth.

DANIEL SHERWOOD.
